UNITED STATES PATENT OFFICE.

CHARLES N. TALBOT, OF FLUSHING, NEW YORK.

DEVICE FOR SYNCHRONIZING CLOCKS.

SPECIFICATION forming part of Letters Patent No. 292,962, dated February 5, 1884.

Application filed November 26, 1883. (No model.)

To all whom it may concern:

Be it known that I, CHARLES N. TALBOT, of Flushing, in the county of Queens and State of New York, have invented an Improvement in Synchronizing Clocks, of which the following is a specification.

Efforts have been made to set the hands of clocks by the action of an electric current and magnet through the agency of levers or fingers; but in cases where the hand may be too fast or too slow, and be beyond the reach of the fingers, the device fails to operate.

My invention relates to the combination, in a clock-movement, of a frictional connection between the hand and the clock-movement and a magnetic liberator, by which such clock-hand is liberated and assumes the desired position by gravity. When the liberation takes place at the half-hour, the minute-hand simply falls back to its place at VI on the dial if it has passed beyond, or moves forward if it is slow. When the liberation takes place at the hour, the minute-hand has to be counterpoised sufficiently to turn it to XII on the dial.

In the drawings, Figure 1 is a section representing one of the modes in which my invention can be carried into use, and Fig. 2 represents the weighted hand.

The shaft *a* is supported in the frames *b b* and rotated by the clock-movement and gear-wheel *c*. This shaft *a* is tubular, and within it is the arbor *e* of the minute-hand *f*. These parts are to be connected by any suitable frictional coupling, and the magnetic liberator disconnects the arbor *e* from the frictional contact with the shaft *a* by an endwise movement given to the arbor *e*. To effect this operation I have represented the armature-lever *g* as pivoted at *h* and acted upon by the electro-magnet *k*. The end of the arbor *e* is pointed, and bears against the jewel or hardened plate *i* upon the armature-lever, and there is a helical or other spring at *l*, to move the arbor *e* toward the lever *g* and to apply the friction to the parts which cause *a* and *e* to move together; but when the electro-magnet *k* is energized the armature-lever gives an end movement to the arbor *e*, compressing the spring *l* and lib-

erating the frictional device, so that the hand *f* is free to turn and assume a vertical position, either by its own weight bringing it to VI or by a counterpoise bringing it to XII.

It is to be understood that the electro-magnet *k* is to be energized a few seconds before the time to which the hand is to be set, so that there may be time for the hand to cease oscillating; and when the electric current is interrupted the frictional device reconnects the hand to the clock at exactly the time denoted by the hand.

I have shown a disk, *o*, upon the hollow shaft *a*, with a beveled edge, and a hollow wheel, *r*, upon the arbor *e*, to form the frictional coupling to connect *a* and *e*, and to allow for the disconnection by the end motion of *e*. This wheel *r* may be one of the train *r s t u*, that gives motion to the hour-hand *v* from the arbor *e*, these gear-wheels being proportioned as usual. In this case the two hands will always be moved together; but the minute-hand must have sufficient weight and leverage not to be influenced by the hour-hand. The latter may be balanced; but when the clock is only to be set at twelve o'clock both hands may be provided with a sufficient counterweight to bring them up to XII on the dial.

I claim as my invention—

1. The combination, with the clock and its hands, of a frictional connection between the minute-hand arbor and the clock-work, and an electro-magnet to liberate the frictional connection and allow the hand to assume its true position by gravity, substantially as set forth.

2. The combination, in a clock, of an arbor, a minute-hand upon the same, a frictional connection between the arbor and the clock-work, and an electro-magnet, and armature-lever to give end motion to the arbor and liberate the frictional connection, substantially as set forth.

Signed by me this 24th day of November, A. D. 1883.

CHARLES N. TALBOT.
